F. DARBY

LOCOMOTIVE TENDER

Filed Aug. 29, 1927

UNITED STATES PATENT OFFICE.

FREDERICK DARBY, OF CHICAGO, ILLINOIS.

LOCOMOTIVE TENDER.

Application filed August 29, 1927. Serial No. 216,257.

My invention relates to improvements in tenders for locomotives, and it consists in the combinations, constructions, and arrangements herein described and claimed.

The coal hoppers of the ordinary locomotive tender are very often filled with coal which is heaped up beyond the sides of the tender to such an extent that the lumps of coal tend to work down and fall off from the sides during the movement of the locomotive, thus wasting coal and furthermore rendering it dangerous for persons who are on platforms past which the locomotive is proceeding, since lumps of coal are apt to be thrown from the moving locomotive and may strike one who is beside the track.

An object of my invention is to provide a locomotive tender having means whereby the danger of coal falling off from the side of the hopper is eliminated.

A further object is to provide a tender having a hopper which may be loaded in the ordinary way and in which the excess coal may fall off into the bin, and being provided with retaining members which can be shifted so as to prevent any further falling off of the coal.

A further object is to provide a device of the type described in which hinged extensions of the sides of the hopper may be moved simultaneously to an inclined position ready for the loading of the hopper and the falling off of the excess coal into the coal bin, said means being adapted to shift the extensions to a position to prevent further loss of the coal.

Other objects and advantages will appear in the following specification, and the novel features of the invention will be particularly pointed out in the appended claims.

My invention is illustrated in the accompanying drawings, forming part of this application, in which

Figure 1 is a plan view of a portion of a locomotive tender constructed according to my invention,

Figure 2 is a sectional view along the line 2—2 of Figure 1,

Figure 3 is a side view of a portion of the inner wall of the hopper shown in Figure 1, and

Figure 4 is an enlarged sectional view along the line 4—4 of Figure 2.

In carrying out my invention, I make use of a tender 1 of ordinary construction and

having a coal hopper 2. The side walls of the hopper are indicated at 3.

Hingedly secured to the top edges of the side walls 3 are extensions 4. It will be observed that the hinges 5 are disposed near the ends of the hopper, the brackets for the hinges being on the inner side of the hopper. The extensions are in the form of plates and are of sufficient width to overlap the side walls, as shown in Figure 2. The purpose of this overlapping will be explained later.

Secured to an end wall 6 of the hopper is a lever 7. In Figure 4, I have shown the manner in which this lever is mounted. It will be observed that there is a boss 8 on the end wall 6 and a bolt 9 passes through the boss and the end wall and is secured by means of a nut 10 and washer 11. The lever 7 is pivotally mounted on an enlarged portion of the bolt and is held in position by a nut 12 and a washer 13.

Secured to the lever above the pivot bolt 9 is a link 14 which is pivotally connected to one of the extensions 4, while a similar link 15 is secured to the lower end of the lever and is pivotally secured to the other extension 4. The lever 7 is provided with a locking pin 16 which may enter notches such as that shown at 17 in a locking arm 18 carried by a bracket 19.

From the foregoing description of the various parts of the device, the operation thereof may be readily understood. When it is desired to load the hopper with coal, the locomotive is moved so that the hopper is underneath the delivery chute and the lever 7 is moved into the position shown in dotted lines in Figure 2. In order to accomplish this, the locking arm 18 is raised and the lever is then shifted and the arm is dropped over the pin 16. The shifting of the lever will bring the extensions 4 into the dotted-line position shown in Figure 2, where they rest on brackets such as those shown at 20.

The coal may now be loaded into the hopper and if an excess amount of coal is delivered, it will fill the hopper and will overflow, falling off the inclined extensions 4 into the coal bin. When the hopper has been loaded, the lever 7 is now shifted to the full-line position shown in Figure 2 and locked with the locking arm 18. This will swing the extensions into vertical positions in substantial alignment with the sides, the lower part of the extensions then abutting the sides

of the hopper, as shown in Figure 2. Thus the extensions are held on one side of the pivot by direct contact with the side of the hopper and on the other side of the pivot 5 by the links 14 and 15.

Now it will be observed that there is a space between the extensions and the body of the heaped up coal which is indicated in dotted lines at 21 in Figure 2. Any coal which 10 tends to shake down toward the sides will be caught and retained in the angle between the coal body and the extensions, thereby preventing any coal from falling off from the hopper. It is customary to load a hopper to its fullest capacity, and with the ordinary construction some of the coal is sure 15 to be shaken down and will fall off from the sides. With the present invention, however, this is entirely prevented.

20 In order to insure that the hinged extensions will not be broken off and thrown from the moving locomotive, I have provided safety chains 22 which are attached at one end to the extensions 4 and at the other end to the walls 3 of the hopper. If, for instance, the 25 pindle of the hinge should happen to work loose, the extension will be kept from falling off by these chains which will permit free movement of the extensions, but will prevent their dropping off in case they should become loosened.

30 I claim:

1. A locomotive tender having a coal hopper, hinged extensions carried by the sides of the hopper at the upper edges thereof, 35 and means for swinging said extensions inwardly at an angle to the sides and for swinging said extensions into substantially vertical alignment with the sides.

2. A locomotive tender having a coal hopper, hinged extensions carried by the sides 40 of the hopper at the upper edges thereof,

means for swinging said extensions inwardly at an angle to the sides and for swinging said extensions into substantially vertical alignment with the sides, and means for rigidly holding said extensions in either position. 45

3. A locomotive tender having a coal hopper, hinged extensions secured to the sides of 50 said hopper at the upper ends thereof, means for simultaneously swinging said extensions inwardly at an angle to the sides and for simultaneously swinging the extensions outwardly in substantially vertical alignment 55 with the sides, and means for holding the extensions rigidly in either of their shifted positions.

4. A locomotive tender having a coal hopper, hinged extensions secured to the sides 60 of said hopper at the upper ends thereof, means for simultaneously swinging said extensions inwardly at an angle to the sides and for simultaneously swinging the extensions outwardly in substantially vertical alignment 65 with the sides, means for holding the extensions rigidly in either of their shifted positions, and flexible means connecting the sides of the hopper with said extensions 70 for preventing the accidental dislodgment and the dropping of the extensions from the sides. 75

5. A locomotive tender having a coal hopper, hinged extensions carried by the sides 80 of said coal hopper at the upper ends thereof, means including a lever and links for moving both of said hinged extensions simultaneously to a position inclined with respect to the sides and for moving them into parallelism with the sides, and means for locking the moving mechanism to hold the extensions rigidly in either of their shifted positions. 85

FREDERICK DARBY.
